UNITED STATES PATENT OFFICE.

CLARENCE WARNER AND HARRY B. HULL, OF DAYTON, OHIO, ASSIGNEES, BY MESNE
ASSIGNMENTS, TO FRIGIDAIRE CORPORATION, A CORPORATION OF DELAWARE.

REFRIGERATING APPARATUS.

Application filed November 6, 1924, Serial No. 748,248. Renewed November 27, 1926.

The present invention relates to refrigerating apparatus and particularly to mechanical refrigerating apparatus including an evaporator in which food and desserts are congealed or in which water is frozen.

One of the objects of the present invention is to freeze the water or congeal the food in a more efficient manner. This object is carried out by constructing the evaporator and the container for said water or dessert in such a manner so that said container can be placed relatively close to the evaporator.

It is a further object of the present invention to provide for the ready removal of the container which is likely to be frozen upon its support.

Further objects and advantages of the present invention will be apparent from the following description reference being had to the accompanying drawings, wherein a preferred form of the present invention is clearly shown.

Referring to the drawings, Fig. 1 is a diagrammatic view of a mechanical refrigerating apparatus embodying the present invention. Fig. 2 is an enlarged fragmentary sectional view of the cooling unit showing a portion of the container, and Fig. 3 is a front elevation of the container showing same in the position in which it is placed for withdrawing same.

Referring to the drawings, a refrigerating apparatus is shown including a compressor 20 for expanding refrigerant contained within an evaporator 21 through the pipe 22 and for compressing the refrigerant and forcing same into a condenser 23, from where the condensed refrigerant is conducted by a pipe 24 to an expansion valve 25 which controls the flow of refrigerant to the evaporator 21. The compressor 20 is driven by belt-and-pulley connections 26, 27 and 28, by a motor 30.

The evaporator 21 comprises a series of coils 31. These coils form a support for a shelf 32 and are suitably connected with said shelf by soldering or brazing same as is shown at 33, in order to provide for the ready conduction of heat from said shelf to the coils 31. Containers for water to be frozen

or food to be congealed are slidably mounted upon the shelf 32. The entire bottom wall 36 of the container 35 engages the top side of the shelf 32 and this relatively large contact surface provides for the ready conduction of heat from the container 35 to the support 32.

Due to condensation, water is likely to freeze upon the shelf 32 and cause the container 35 to be frozen tightly to the shelf. In order to readily remove the container 35 from the shelf 32, it is necessary, first, to break the ice bond between said container and shelf. Therefore, the handle 37 for the container 35 is pivotally mounted at 38 upon extending portions 40 of the side walls of the container. Downwardly extending arms 39 are formed integrally with the handle and are adapted to engage the shelf 32 when the handle 37 is moved to remove the container. This movement of the handle 37 will cause the container 35 to be lifted as shown in Fig. 3 and in the dotted-line position (Fig. 2), which will cause the ice bond between the container 35 and the shelf 32 to be broken. The handle 37 and arms 39 form bell-crank levers and the construction and arrangement of said levers with respect to the shelf 32 is such, that by merely pulling the handle 37 horizontally, for removing the container 35, a vertical movement will be imparted to the container for breaking the ice bond, whereby the container can be removed readily.

While the form of embodiment of the invention as herein disclosed, constitutes a preferred form, it is to be understood that other forms might be adopted, all coming within the scope of the claims which follow.

What is claimed is as follows:

1. A cooling device, comprising in combination, a plurality of cooling coils, a shelf supported by said coils, a slidable container supported by said shelf, and means pivoted to said container and having an arm adapted to engage said shelf, for breaking an ice bond between the container and the shelf. 95

2. A cooling device, comprising in combination, a plurality of cooling coils, a shelf supported by said coils, a slidable container

supported by said shelf, a bell crank lever pivoted to the container and having an arm adapted to engage said shelf, for breaking an ice bond between the container and the shelf.

5 3. A cooling device, comprising in combination, a plurality of cooling coils, a shelf supported by said coils, a slideable container supported by said shelf, a handle pivoted to the container, and means associated with said handle and adapted to engage said shelf when said handle is rocked on its pivot, for breaking the ice bond between the container and the shelf.

10 4. A cooling device, comprising in combination, a plurality of cooling coils, a shelf supported by said coils, a slideable container supported by said shelf, a movable handle pivoted to said container, and means carried by said handle and adapted to engage said shelf upon movement of the handle, for breaking an ice bond between the container and the shelf.

15 5. A cooling device, comprising in combination, a plurality of cooling coils, a shelf supported by said coils, a slideable container supported by said shelf, a bell crank lever pivoted to said container, one arm of said lever serving as a handle, the other arm being adapted to engage said shelf upon movement of said handle to withdraw said container.

20 6. Refrigerating apparatus comprising in combination, an ice-making container having a surface adapted to cooperate with a support, a handle movably secured to the container, and means operated by movement of the handle with respect to the container adapted to separate the surface from such support when force is applied to the handle substantially parallel to the surface.

25 7. Refrigerating apparatus comprising in combination, an ice-making container having a surface adapted to cooperate with a support, a handle movably secured to the container, and means normally on one side of the plane of the surface operated by movement of the handle under the influence of force substantially parallel to the surface to project on the other side of the plane of the surface.

30 8. Refrigerating apparatus comprising in combination, an ice-making container having a surface adapted to cooperate with a support, a handle pivoted to the container and including a portion adapted to engage the support, said engaging portion being adapted to be moved to a position on one side of the plane of said surface by movement of the handle with respect to the container under the influence of force in one direction parallel to said surface, and to be moved to a position on the other side of the plane of said surface by movement of the handle under the influence of force applied parallel to the surface in the opposite direction.

35 9. In refrigerating apparatus, a container

to be cooled, cooling means in thermal contact with the container, means operatively connected to the container for removing the container from the cooling means, and means actuated by the removing means for breaking an ice bond between the container and cooling means.

10 10. In refrigerating apparatus, a container to be cooled, cooling means in thermal contact with the container, means operatively connected to the container for removing the container from the cooling means, and means actuated by the removing means for separating the container from the cooling means.

15 11. In refrigerating apparatus, a container to be cooled, cooling means in thermal contact with the container, means operatively connected to the container for moving the container along the surface of the cooling means, and means actuated by said moving means for separating the container from the cooling means.

20 12. In refrigerating apparatus, a container to be cooled, cooling means in thermal contact with the container, means operatively connected to the container for moving the container along the surface of the cooling means, and means operated by said moving means for moving the container perpendicularly to the surface of the cooling means.

25 13. In a refrigerating apparatus, a container to be cooled, a support for the container, means operatively connected to the container for moving the container along the surface of the support, and means actuated by the moving means for separating the container and support.

30 14. In a refrigerating apparatus, a container to be cooled, a support for the container, means operatively connected to the container for moving the container along the surface of the support, and means operated by the moving means for moving the container perpendicularly to the support.

35 15. In refrigerating apparatus, a container to be cooled, a support for the container, a handle adapted to move the container along the surface of the support and movably attached to the container, and means operated by movement of the handle with respect to the container for breaking an ice bond between the container and support.

40 16. In refrigerating apparatus, a container to be cooled, a support for the container, a handle adapted to move the container along the surface of the support and movably attached to the container, and means operated by movement of the handle with respect to the container for moving the container perpendicularly to the surface of the support.

45 17. In refrigerating apparatus, a container to be cooled, a support for the container, means operatively connected to the container for moving the container in one

direction and means operated by the moving means for moving the container in a direction transverse to the first mentioned direction.

18. In refrigerating apparatus, in combination, a container to be cooled, a handle pivoted to the container and including a lever, a support for the container, the lever being adapted to bear against the support to sepa-

rate the container from the support when force is applied to the handle in a direction 10 to slide the container off the support.

In testimony whereof we hereto affix our signatures.

CLARENCE WARNER.
